COMBINED DISPLAY AND DISPENSING CASE

Fred O. Kolstad, 18733 Plummer St., Northridge, Calif.

Filed July 22, 1963, Ser. No. 75,905

Term of patent 14 years

(Cl. D80—9)

FIG.3.

I claim:

The ornamental design for a combined display and dispensing case, substantially as shown.
